SWIMMING POOL CHLORINATOR

Donald Frascone, Bronx, N.Y. (% Ortex Products, Inc., 560 Ferry St., Newark, N.J. 07015)

Filed Nov. 17, 1971, Ser. No. 199,818

Term of patent 14 years

Int. Cl. D23—01

U.S. Cl. D23—3

FIG. 3

FIG. 1

FIG. 4

FIG. 2

FIG. 1 is a side elevational view of a swimming pool chlorinator embodying my new design.

FIG. 2 is a top plan view thereof.

FIG. 3 is a rear elevational view thereof; and

FIG. 4 is a front elevational view thereof.

I claim:

The ornamental design for a swimming pool chlorinator, substantially as shown.
